UNITED STATES PATENT OFFICE.

CHARLES O. YALE, OF NEW YORK, N. Y., ASSIGNOR TO HERBERT P. BROWN
AND MARIE LOUISE YALE, OF SAME PLACE.

LOADING AND DISCHARGING GUNS.

SPECIFICATION forming part of Letters Patent No. 424,043, dated March 25, 1890.

Application filed November 5, 1888. Serial No. 290,022. (No model.)

To all whom it may concern:

Be it known that I, CHARLES O. YALE, a citizen of the United States, residing in the city, county, and State of New York, have invented certain new and useful Improvements

in Loading and Discharging Guns, of which the following is a description in such full, clear, and exact terms as will enable any one skilled in the art to which my invention applies or with which it is most nearly connected to make and use the same, reference being had to the accompanying drawings, making part of this specification, and to the letters of reference marked thereon.

My invention consists of a novel manner of placing the explosive charge in and combining it with the breech of a gun, and has for its object, among other things, to diminish the cost of constructing guns, and especially heavy ordnance, to decrease their liability to fracture and burst, and to permit the use of high explosives in guns designed and constructed for ordinary gunpowder.

My invention is principally designed to be used in connection with heavy ordnance of all kinds, and permits a more extended use of high explosives—such as dynamite—for the explosive charge.

High explosives—such as dynamite—have heretofore been used instead of gunpowder in heavy guns; but while their projectile efficiency is very great, on account of the very high rate of expansion of the gases generated at their discharge, and also on account of the almost instantaneous character of their explosion, very heavy and specially-constructed guns have been required for their use to withstand the sudden shock of the explosion, and the results have been only partially satisfactory. Among other things, my invention is designed to decrease the cost of guns in which such high explosives are used and to increase their efficiency.

As is now well understood, in the use of gunpowder or other explosive agents the great heat generated at the instant of the explosion and the dynamic force incident thereto act like driving millions of wedges against the interior surface of the barrel, which sooner or later fracture or crack the metal and destroy the utility of the gun. By

my invention the effect of this action is greatly decreased and the life of the gun is correspondingly increased, besides permitting the use of lighter and less expensive barrels.

My invention consists in placing the explosive charge of the gun so that it may be wholly or partially surrounded by a cushion of air or other elastic gaseous envelope when it is in place for firing, and so that it shall at no points of its side touch the interior concave walls of the gun-barrel. As air is a very poor conductor of heat, the destructive action of the very high temperature incident to an explosion is to a large extent obviated. As air is to a very high degree elastic, the effect of the shock of the explosion is greatly diminished and is spread evenly over the whole interior surface of that part of the barrel subjected to it. The elastic cushion of air also adds to the effectiveness of the projectile capacity of the charge by a more advantageous application of the dynamic force of the explosion. The cushion or envelope of air may be employed at atmospheric or at any other suitable pressure. Compressed air may be more advantageously employed in some instances and may readily be obtained in a muzzle-loading gun—for instance, by having the projectile packed to fit the bore when it is driven home to its lodgment in the barrel.

The following is an illustration of how my invention may be practically applied: Within the breech of a gun designed to receive a cartridge of powder, for instance, let there be suspended or placed by any suitable means, centrally, a cartridge containing dynamite of a projectile capacity equal to the capacity of the gunpowder cartridge which the chamber was designed to receive. As dynamite is much more powerful than gunpowder for a given bulk, the dynamite cartridge will be considerably smaller than the breech-chamber behind the projectile. It will therefore be surrounded on its sides and behind with an air space or cushion. I prefer also to leave a small air-space between the front end of the cartridge and the rear end of the projectile; but this may be dispensed with. By thus placing and arranging the dynamite cartridge

it will be seen that while the efficiency of the gun is not diminished, but is increased, its life will be, on account of the considerations herein pointed out, considerably augmented.

5 If a larger charge of dynamite be employed, a greater efficiency can be obtained without decreasing the normal life of the gun.

In the accompanying drawings one means of utilizing my invention is illustrated.

10 Figure 1 of said drawings illustrates in longitudinal section a gun-barrel containing the projectile and cartridge; and Fig. 2 illustrates, partly in perspective and partly in section, the projectile, cartridge, and means for centering and firing the same.

15 The following is a description of the devices illustrated in the drawings:

A is a gun-barrel bored to the proper size.

20 B B' are re-enforcing rings to strengthen its breech.

D is a breech-plug screwing in the breech of the gun.

E is the projectile, and H the cartridge. As a suitable means of maintaining the cartridge 25 in its proper position with relation to the projectile and the inclosing-walls of the gun-barrel, I have shown the projectile provided with a central projection F at its rear end and the cartridge provided with a tube G, 30 projecting from its front end, made of suitable material—such as paper—slipping over and fitting the projection F of the projectile. I have also shown the cartridge provided with a ring or washer I of suitable material—such 35 as paper—which surrounds the cartridge, and which maintains it at its proper position centrally within the barrel. As a means of exploding the cartridge, I have shown a rod J passing through the breech-plug and capable 40 of longitudinal movement therein, on the forward end of which a needle K is attached, bearing against the fulminate placed in the rear end of the cartridge. When this rod J is driven in, the forward end of the needle attached thereto, bearing against the fulminate, 45 discharges the cartridge. As a means of protecting the fulminate in the rear end of the cartridge, I have shown a sleeve L attached thereto and projecting beyond it.

50 Among the advantages incident to the use of dynamite as a substitute for gunpowder may be mentioned the fact that the length of

the gun-barrel may be diminished on account of the more rapid ignition of the explosive, as the barrel must be long enough to insure 55 the complete combustion of the explosive before the projectile is discharged from it.

As I have before said, gunpowder may thus be used as well as dynamite or other high explosive, and a saving thereby be effected 60 in the weight of the gun, while its efficiency is augmented and its life prolonged.

I have described my invention as applied to heavy ordnance; but it is apparent that it is applicable to all kinds of guns, and that 65 the principle of my invention may be utilized with many modifications as to detail, both in the construction of the gun and of the cartridge, without departing from its general principle, purpose, or design. I have said 70 that I prefer to leave an air-space between the front end of the cartridge and the rear end of the projectile, and my object in doing this is to more efficiently apply to the projectile the force generated in the explosion; 75 but such space is not essential, and may be, if desired, omitted.

The essential part of my invention is the protection by an elastic cushion—such as air—of the vulnerable parts of the gun from 80 the effects of the intense heat and force generated at the instant of the explosion.

What I claim is—

1. In a gun, the combination of a projectile, a cartridge of explosive material, a cushion 85 of gas surrounding said cartridge and completely isolating it from the interior surfaces of the gun-barrel, and a supporting-frame by means of which the cartridge is held in position without contact with the walls of the 90 gun-barrel, substantially as described.

2. In a gun, the combination of a projectile, a cartridge of high explosive material—such as dynamite—a cushion of gas surrounding 95 said cartridge and completely isolating it from the interior surfaces of the gun-barrel, and also from the projectile, and a supporting-frame by means of which the cartridge is held in position, substantially as described.

CHARLES O. YALE.
